Primary Examiner — Mark Goodwin

(74) Attorney, Agent, or Firm — Weiss & Arons LLP; Avi Goldenberg, Esq.

(57) **CLAIM**

The ornamental design for a snow pusher, as shown and described.

DESCRIPTION

FIG. 1 is a top, front, left perspective view of a snow pusher showing our new design;

FIG. 2 is a front elevational view thereof;

FIG. 3 is a rear elevational view thereof;

FIG. 4 is a left side elevational view thereof, the right side being a mirror image;

FIG. 5 is a top plan view thereof; and,

FIG. 6 is a bottom plan view thereof.

The broken line showing of the environment is for illustrative purposes only and forms no part of the claimed design.

1 Claim, 6 Drawing Sheets**FIG. 1**

FIG. 2

FIG. 3

FIG. 4

FIG. 5

FIG. 6
